UNITED STATES PATENT OFFICE.

GLENN AUGUSTUS MILLER, OF BOULDER, COLORADO.

PISTON FOR OIL-WELLS.

SPECIFICATION forming part of Letters Patent No. 780,518, dated January 24, 1905.

Application filed October 28, 1903. Serial No. 178,918.

To all whom it may concern:

Be it known that I, GLENN AUGUSTUS MILLER, a citizen of the United States, residing at Boulder, in the county of Boulder and State of Colorado, have invented a new and useful Pump-Piston for Oil-WellS, of which the following is a specification.

My invention relates to pump-pistons for wells, and more particularly for wells provided with a casing—as, for instance, oil-wells, &c.

In pumping oil great difficulty is often experienced in having the sand or other gritty material cutting out the leather washers or cups used for making a close joint and securing more prompt suction or action of the piston in operation.

The object of my invention is to prevent access of sand or other gritty material to the cups or washers, thereby preventing excessive wear as the piston is reciprocated within the working barrel. I accomplish this object by constructing a substantially cylindrical piston the central portion of which is reduced and the ends are in the form of hollow cylinders, the lower cylinder being open and the upper cylinder being provided with a suitable valve.

In the accompanying drawings, in which the same letters of reference indicate corresponding parts in each of the views in which they occur, Figure 1 is a longitudinal sectional view of a portion of the working barrel of a pump with my improved piston in position therein. Fig. 2 is a similar view showing the piston in section.

Referring to the drawings, A indicates a section of the casing of a well and which also serves the purpose of a working barrel within which is located my improved piston, one form of the piston which I have found very efficient consisting of a central section B and two end cylinders C, the central section being hollow throughout its length and joined to the inner ends of the end sections, as by means of annular nuts D. Arranged upon the central section are the leather cups E, which are spaced apart and held in positions by rings F, formed of metal or other suitable material.

These rings F bear upon the bottom portions 50 of the cups E, and the sides of the cups stand out clear of the rings and in contact with the inner face of the working barrel. The exterior diameter of the end cylinders are substantially equal to the diameters of the cups 55 and are sufficient to cause a snug fit with the interior of the working barrel when the parts are in position for operation. The upper end of the upper cylinder is provided with a suitable valve structure comprising a body portion G, having a longitudinal bore there-through and a valve-cage H at its upper end. The lower end of the body may be reduced and screw-threaded for engaging with the upper end of the cylinder, and the intermediate portion may be square or angular for the reception of a wrench in securing it to the end of the cylinder. A valve I, preferably a ball-valve, may be placed loosely within the cage and adapted to rest upon its seat formed 70 at the upper end of the bore through the body portion. A suitable valve structure J is secured within the casing below the lower end of my improved piston and may be of any ordinary form.

By constructing a piston as above described it is evident that when it is inserted in the working barrel the long cylindrical surface of the cylinders at each end will prevent the entrance of sand or other material to the 80 leather cups, which are seated, preferably, substantially midway of the length of the piston. The entrance of the sand between the piston and the working barrel is further prevented by the square shoulders formed at the 85 ends of the working barrel, which will engage with the sand that may be sticking upon the interior of the barrel and push it along ahead of the piston, and thereby prevent its coming in contact with the cups, owing to the 90 length of reciprocation of the pistons as compared with its length.

In operation the piston is inserted into the pump after being connected with the usual pump-rod and reciprocated in the ordinary 95 manner. At any time that the cups become worn or need replacing the piston is separated, as by unscrewing either one of the cylinders

from the central portion, after which the cup can be repaired or replaced and the parts screwed together again.

Although I have shown what I consider the 5 best form of construction of my improved piston, it is evident that alterations or changes may be made therein, and I reserve the right to make all such changes as will come within the scope of my invention.

10 Having thus fully described my invention, what I claim as new, and desire to secure by Letters Patent, is—

15 A device of the kind described comprising a working barrel, a piston consisting of end cylinders fitting snugly within the barrel, and an intermediate section connecting the end

cylinders, said section being of less diameter than the end cylinders, nuts connecting the reduced intermediate section to the end cylinders, a valve-cage having a threaded body portion secured in the upper end of one of the end cylinders, said body portion having a bore formed longitudinally therethrough, a ball-valve in said cage, cups having a diameter equal to that of the end cylinders, and rings spacing the cups apart, said cups and rings being carried by the intermediate section. 20 25
